UNITED STATES PATENT OFFICE.

MOSES H. EISEMAN, OF CHICAGO, ILLINOIS.

COIN-HOLDER FOR POCKET-BOOKS, PURSES, &c.

SPECIFICATION forming part of Letters Patent No. 663,016, dated December 4, 1900.

Application filed February 17, 1900. Serial No. 5,574. (No model.)

To all whom it may concern:

Be it known that I, MOSES H. EISEMAN, a citizen of the United States, residing at Chicago, in the county of Cook and State of Illinois, have invented certain new and useful Improvements in Coin-Holders for Pocket-Books, Purses, and the Like, of which the following, when taken in connection with the drawings accompanying and forming a part of the same, is a full and complete description, sufficient to enable those skilled in the art to which it pertains to understand, make, and use the same.

One object of this invention is to obtain a coin-holder which may be placed between the outer and inner cover in an ordinary pocket-book or purse to hold dimes or nickels, as for street-car fare, in such manner that the same may be readily released by the hand holding the pocket-book, one at a time, when wanted without opening the pocket-book and without removal of the cover by the person using the pocket-book.

A further object is to obtain a compartment, separated from and independent of the rest of the pocket-book, in which coin for street-car fare or for other purposes may be placed, so that the contents of the pocket-book other than the coin contained in the device embodying this invention may be used without thought or reference to car-fare or other matter or thing for which coin has been reserved in such coin-holder.

In the drawings referred to as forming a part of this specification, Figure 1 is a top plan view of a coin-holder embodying this invention; Fig. 2, a side elevation thereof; Fig. 3, an end elevation, as on the end provided with dotted line 3 3 of Fig. 1, looking in the direction indicated by the arrows, crossing such dotted line; Fig. 4, an end elevation of the opposite end of the coin-holder, such view being also indicated by a dotted line which is lettered 4 4 and having arrows thereon indicating the point of view; Fig. 5, a perspective view of one side and end of a pocket-book having the device embodying this invention, which is illustrated in Figs. 1 to 4, all inclusive, inserted therein.

50 A reference-letter applied to designate a given part is used to indicate such part

throughout the several figures of the drawings wherever the same appears.

A is a coin-holder, preferably made of sheet metal and formed up to make the body 55 part and the folded edges a a', thereby obtaining the grooves a², in which grooves the coin slides.

a³ is a stop at the inner end of the coin-holder, designed to prevent a coin from passing out from the coin-holder in between the outer and inner cover of the pocket-book.

B is a movable retaining device at the outer end of the coin-holder, yieldingly held in a closed position and when closed having the 65 handle or operating part b thereof extended, so that the same may be retracted by pressing the same through the outer cover of the pocket-book in which the device is obtained. When this retaining device B, as is illustrated in the drawings, is of spring sheet metal the parts b' b' constitute the springs holding the handle b in an extended position and the retaining end b² in position closing the outlet of the device. 70

b² b³ are also retaining projections designed to be held in a retracted position when the retaining end b² is extended to close the outlet of the coin-holder and to be forced into a retaining position when the handle b is depressed and the retaining end b² is retracted. 80 By means of the retaining projections b³ but one coin is delivered at a time, although the coin-holder be filled at the time. The fold or bend a' is cut away, as indicated by the dotted 85 line C, to permit the retaining projections b² b³ to move forward into operative or retaining position, as last above described.

D D are the fulcrums on which the retaining device B turns and may be formed, as 90 illustrated, integral with the metal sheet from which the coin-holder B is bent up, as above described.

The coin-holder constructed as above is readily inserted between the outer and inner 95 cover of the flap of a pocket-book or between the outer and inner cover of the flap of a pocket in a body-belt, chatelaine-bag, or other like place, so that the end of the coin-holder having the retaining device will discharge a 100 coin, when the device is operated, into the hands of the person holding or wearing the

same. In Fig. 5 of the drawings the device is shown, as hereinbefore stated, placed in the flap of a pocket-book; but I do not limit myself to placing such coin-holder in such flap.

To operate this device, the retaining device B is retracted by pressing upon the handle thereof through the outer cover of the flap F and a coin inserted in the coin-holder. The 10 operation is repeated for each coin inserted therein until the coin-holder has the desired number of coins therein or is filled. To use one of such coins, the pocket-book is turned so that the coins will fall by gravity with one 15 thereof close to contact with the retaining device B. The handle of the retaining device is depressed, and a coin will drop out from the coin-holder for use.

By means of this device a lady may, when 20 the same is placed in a pocket-book, body-belt, or chatelaine-bag, at all times easily obtain car-fare without removing her gloves and with but little trouble.

The advantages of the device are particularly great when many parcels or packages 25 are being carried by the person using the device.

Having thus described my invention and the manner in which it is operated, what I 30 claim as new, and desire to secure by Letters Patent, is—

1. The combination of a coin-holder with a pocket-book, such coin-holder consisting of a coin-receptacle inserted between the inner 35 and the outer cover of one flap of the pocket-book and a retaining device yieldingly held in an extended position closing the outer end of the coin-receptacle and provided with a handle operative through the outer cover of 40 the flap to retract such retaining device without opening the pocket-book; substantially as described.

2. The combination of a coin-holder with a pocket-book, such coin-holder consisting of a coin-receptacle inserted between the inner 45 and the outer cover of one flap of the pocket-book, the coin-receptacle comprising a blank

bent up to obtain grooves in which the coin slides and a retaining device yieldingly held in an extended position closing the outer end 50 of the coin-receptacle and provided with a handle operative through the outer cover of the flap to retract such retaining device without opening the pocket-book and also provided with retaining projections which are extended into the path of the coin back of the one released thereby retaining them; substantially as described.

3. A coin-holder consisting of a blank bent up along the edges of the sides, to form 60 grooves, a stop at the inner end of the holder to retain coin therein and a retaining device yieldingly held in an extended position closing the outer end of the holder, a fulcrum on which the retaining device turns, retaining 65 projections on the retaining device back of the fulcrum thereof, such retaining projections adapted to be retracted from the path of the coin when the outer end of the coin-holder is closed by the retaining device and 70 to be projected into the path of the coin when the retaining device is retracted to permit a coin to pass from the holder and such retaining device being provided with a handle by which it may be operated; substantially as 75 described.

4. A coin-holder consisting of a blank bent up to obtain grooves, a stop at the inner end of the holder and a retaining device yieldingly held in an extended position at the outer 80 end of such holder, retaining projections yieldingly held in a retracted position and attached to the retaining device, a fulcrum between the outer end of the retaining device and the retaining projections attached thereto, and the retaining device provided with a handle, in combination with a pocket-book between the outer and inner covers of one flap whereof the coin-holder is inserted; substantially as described.

MOSES H. EISEMAN.
